HARMONICA

Paul K. Moore, Denver, Colo.

Application January 12, 1937, Serial No. 120,193

12 Claims. (Cl. 84—377)

This invention relates to improvements in harmonicas.

It is an object of the invention to provide a harmonica having means whereby the musical key thereof can be selectively varied.

Another object is to provide a harmonica wherein the notes or tones may be sharped or flatted.

A further object is to make a harmonica having pre-set stops for the key-changing mechanism to facilitate the change.

A still further object is to furnish a harmonica wherein both reed-plates and the air-passages corresponding thereto can be selectively shifted as a unit to effect a key change.

Still another object is to provide a harmonica having blow and draw holes in the mouthpiece, so arranged and spaced as to produce the normal musical scale tones in proper sequence in all keys to which the instrument may be set.

Other objects and advantages reside in the details of construction which will be more fully disclosed in the following description and in the drawing wherein like parts have been similarly designated and in which;

Figure 1 is a plan view of a harmonica embodying the invention;

Figure 2 is a side view, partly in section, taken along the lines 2—2 of Figures 1 and 5;

Figure 3 is a fragmentary sectional view on an enlarged scale, taken along the line 3—3 of Figure 1;

Figure 4 is a sectional view taken along the line 4—4 of Figure 1;

Figure 5 is a sectional view taken along the line 5—5 of Figure 2; and

Figure 6 is a fragmentary sectional view taken along the line 6—6 of Figure 2.

In the drawing reference character 12 denotes a mouthpiece divided, by a series of partitions 13, into rectangular cells 14, each connected with a draw passage and a blow passage that communicate respectively, with the draw reeds and blow reeds. The reeds are arranged in half-tone steps, the draw side being shown in Figure 2.

Considering the individual cells 14, beginning at the left end of the instrument, Figure 1, it will be seen that the cells each connect with a blow passage 15 and a draw passage 16. The 50 passages are spaced to register with the reeds to sound the normal scale, do, re, mi, fa, sol, la, ti, do. There is a fulltone space between the first and second passage, and between the second and third, then a half-tone space between the third and fourth, then a full-tone space between the

fourth and fifth, and a full-tone between the fifth and sixth. The details of the sixth passage, which is a draw, are shown at 16a in Figure 2. The object of this special arrangement is to provide a draw in the third cell 14a yet have a full-tone space between the fifth and sixth passage.

A full-tone step is provided by the spacing between the sixth and seventh passage and a half-tone between the seventh and eighth which completes the scale or octave back to "do" again. 10 The upper "do" may be blown from either the fourth cell 14b or the fifth cell 14c by virtue of a special blow passage 15a that communicates with both cells. A flexible valve-flap 17 permits air to be blown downwardly into the passage 15a 15 from either adjoining cell but will check any air from being drawn upwardly through this passage. This arrangement is clearly illustrated in enlarged detail in Figure 3, and prevents a draw on either cell 14b or 14c from affecting the normal draw passage in the other interconnected cell. The reason for having this upper "do" blowable from either cell 14b or 14c is for the convenience of the musician.

The above described sequence of air-passage 25 spacing and arrangement may be repeated for as many octaves as desired, from the highest in treble to the lowest in bass, the example illustrated having four octaves. And it will be seen that regardless of what key or what tone is set 30 for "do" that the correct scale will be sounded in its proper and correct sequence of full-tones and half-tones.

Just below the mouthpiece 12 is a section of flexible material such as rubber 18 that has air-passages 19 therethrough that correspond to and cooperate with the air-conductive blow and draw passages 15 and 16 of the mouthpiece. The upper portion of the rubber 18 is held in stationary relation to the mouthpiece but the lower 40 portion of the rubber is mounted on a slide-guide 20 to which is attached a bifurcated arm 21 so that the thumb or finger of the musician may engage it and by applying longitudinal force thereto, the lower part of the rubber may be 45 flexed to the right or left a distance equal to the individual spacing of the reeds to sharp or flat any note or tone. This movement of the rubber and the passages therein, is indicated in Figure 2 by dotted lines at 19a. A spring 22 passes through a limiting stop 23 and engages a projection 24 of the slide-guide 20 to limit the movement of the rubber and to help return it to its normal position when pressure on the arm 21 is released. The reeds on both the draw reed- 55

plate 25 and the blow reed-plate 26 are equally spaced and all are in half-tone steps. An individual air-passage 27 is located in a reed-block 28 for each reed on both plates, and the reed-plates and reed block are mounted on a slide-rail 29 for longitudinal right and left movement as a unit, therealong, for the purpose of selective key-change, throughout the entire range of the instrument. It will be noted that the blow and draw reed-plates may be made identical each having reeds 30 on the same side of the respective plates but arranged, with reference to instrument, to be actuated by blown air or drawn air respectively.

15 The key-shift mechanism comprises a flat spring-like strip 31 that is pivoted at 32 and that terminates in a finger ring 33. The instrument is housed between side-plates 34 on one of which is the pivot 32 and along the lower edge of which 20 is a notched sector 35. A pin 36 on the strip 31 engages the notches in the sector to selectively hold the reed air-passages 27 in register with the passages 19, and a pointer 37 on the strip indicates the position of the strip with reference to the sector which may be marked as 25 desired to indicate the musical key to which the instrument is set. A connecting rod 38 connects the strip 31 to the movable reed-plate unit at 39 whereby both reed-plates and their supporting 30 reed-block 28 may be shifted along the slide-rail 29. If it is known in advance, to what keys the instrument is to be shifted, during the playing of a composition, the pre-set stops 40 may be set at the pre-determined keys and a quick shift 35 of the strip 31 to the stops 40 can be accomplished for a quick and correct key-change.

The entire instrument may be supported in frame members 41, and it will be seen that this mechanism may be constructed for as many different keys as the musical scale affords. Since 40 all reeds move as a unit, the adjustment or shift covers the entire range of the instrument from the highest treble to the lowest bass. All air passages are correspondingly spaced so that correct register is assured when the various movable elements are in any of their various normal positions. This spacing is based upon the spacing of the half-tone reeds and the limiting stop 23 and the notches in the sector 35 are designed to assure 45 correct air-passage register in the several normal operating positions.

It will be understood that the key-shifting mechanism may be mounted on either side of the instrument. For purposes of clearness it is 55 shown on the near side in Figure 2, but in some cases it may be preferable to mount it on the other side so that it will be more easily seen by the musician when the instrument is at his lips in the playing position.

60 The finger ring on the key-shifting mechanism may, if desired, take the form of a cup or thimble-like structure to prevent the finger from passing therethrough.

What I claim and desire to secure by Letters 65 Patent is:

1. A harmonica comprising a mouthpiece, a reed-plate slidable with reference to the mouthpiece, a plurality of reeds on the reed-plate, there being individual air-passages connecting the 70 mouthpiece with individual reeds, a plate-shifting mechanism including a pivoted arm extending exteriorly of the instrument, and a position-indicating sector.

2. In a harmonica, a reed-plate, a plurality of 75 reeds on the reed-plate, a flexible strip having

air-conductive passages in register with the reeds, and exterior means to flex the strip for changing the register of the passages.

3. In a harmonica, a mouthpiece having air-passages, a rubber section adjacent the mouthpiece there being air-passages in the section in register with the passages in the mouthpiece, a reed-block, a reed-plate on the block there being air-passages in the block in register with the 10 passages in the rubber, and means for shifting the register of the passages in the rubber with reference to the passages in the block. 5

4. In a harmonica, a mouthpiece having air-passages, a rubber section adjacent the mouthpiece there being air-passages in the section in 15 register with the passages in the mouthpiece, a reed-block, a reed-plate on the block there being air-passages in the block in register with the 20 passages in the rubber, and means for shifting the register of the passages in the rubber with reference to the passages in the block by flexing the rubber along one of its sides.

5. In a harmonica, a flexible section having air-passages, a slidable reed-block having air-passages in register with the passages in the section, 25 a reed-plate on the reed-block, and means for flexing the section to change the register of the air-passages.

6. In a harmonica, a mouthpiece having scale-spaced air-passages, a flexible section having air-passages, a slidable reed-block having air-passages in register with the passages in the section, a reed-plate on the reed-block, and means for flexing the section to change the register of 30 the air-passages. 35

7. In a harmonica, a mouthpiece having scale-spaced air-passages, a flexible section adjacent the mouthpiece and having air-passages in register with the passages in the mouthpiece, a slide on the flexible section, a movable reed-block, a 40 reed-plate on the reed-block there being air-passages in the block in register with the passages in the section, means for flexing a portion of the section to change the register of the air-passages therein with reference to the passages 45 in the block, and key-changing means for shifting the block and plate with reference to the instrument.

8. A harmonica comprising a mouthpiece, having air openings differentially spaced therealong 50 in a series of octaves, the openings in each octave being differentially spaced according to the natural sequence of full-tone and half-tone steps in the normal musical scale, a reed-block slidable with reference to the mouthpiece, a reed-plate 55 on the reed-block, and a plurality of reeds on the reed-plate, there being individual air passages in the reed-block in operative communication with the individual reeds and in conductive connection with said openings in the mouthpiece. 60

9. A harmonica comprising a mouthpiece, having air openings differentially spaced therealong in a series of octaves, the openings in each octave being differentially spaced according to the natural sequence of full-tone and half-tone steps in 65 the normal musical scale, a reed-block slidable with reference to the mouthpiece, a reed-plate on the reed-block, and a series of half-tone reeds on the reed-plate, there being individual air 70 passages in the reed-block in operative communication with the individual reeds and in conductive connection with said openings in the mouthpiece. 75

10. A harmonica comprising a mouthpiece, having air openings differentially spaced therealong in a series of octaves, the openings in each octave 75

being differentially spaced according to the natural sequence of full-tone and half-tone steps in the normal musical scale, a reed-block slidable with reference to the mouthpiece, a reed-plate 5 on the reed block, a plurality of reeds on the reed-plate, there being individual air passages in the reed block in operative communication with the individual reeds and in conductive connection with said openings in the mouthpiece, and 10 external means for sliding the reed-block with reference to the mouthpiece for changing the musical key.

11. In a harmonica having a movable reed-block, the improvement which comprises a series 15 of equally spaced half-tone reeds on said reed-block, and a mouthpiece having a series of fixed differentially spaced air openings arranged in a series of octaves, the openings in each octave being differentially spaced according to the sequence of full-tone and half-tone steps in the 20

normal musical octave scale, there being air passages operatively connecting the air openings with the reeds.

12. A harmonica comprising a mouthpiece, having air openings differentially spaced therealong in a series of octaves, the openings in each octave being differentially spaced according to the natural sequence of full-tone and half-tone steps in the normal musical scale, a reed-block slidable with reference to the mouthpiece, a pair of reed-plates 5 on the reed block, a plurality of reeds on each reed-plate, each constituting a chromatic scale, there being individual air passages in the reed block in operative communication with the individual reeds and in conductive connection 10 with said openings in the mouthpiece, and external means for sliding the reed-block with reference to the mouthpiece for changing the musical key.
